UNITED STATES PATENT OFFICE.

LEONARD A. YOUNG, OF HIGHLAND PARK, MICHIGAN.

SEAT-SPRING.

1,211,267.

Specification of Letters Patent. Patented Jan. 2, 1917.

Application filed February 11, 1916. Serial No. 77,741.

To all whom it may concern:

Be it known that I, LEONARD A. YOUNG, a citizen of the United States, residing at Highland Park, county of Wayne, State of Michigan, have invented a certain new and useful Improvement in Seat-Springs; and declare the following to be a full, clear, and exact description of the same, such as will enable others skilled in the art to which it 10 pertains to make and use the same, reference being had to the accompanying drawings, which form a part of this specification.

This invention relates to seat springs and has for its object a seat spring provided 15 with central ties or braces for the supporting springs, that is to say, ties or braces which connect the helical springs from mid portion to mid portion, which ties and braces are of such a character that they 20 form a yielding connection from one side of the seat spring to the other.

In the drawings, Figure 1 is a horizontal sectional view of a part of the seat spring, taken on a plane just above the middle of the 25 seat spring. Fig. 2 is an end view of the seat spring. Fig. 3 is a front view. Fig. 4 is a detail showing how the braces or ties are connected to the mid portions of the helical springs. Fig. 5 is a detail showing 30 how the tops of the helical springs are tied together.

a designates the rim channel bar into which the lower coils of the helical springs are pinched.

b represents the bottom supports for the helical springs, comprising channel bars which are pinched over the lower coils of the springs and located on opposite sides of the helical springs.

c designates the upper rim wire. The helical springs are not braced together at their tops. They are only tied together by loose tie links so that the tops may rock to a certain extent and make the immediate 40 supporting surface of the spring very flexible and yielding, but in order to keep the springs erect and from becoming completely distorted and entangled, it is necessary to brace the springs at their mid portion. This 45 much of the construction is broadly old.

My improvement consists in the nature of the central ties and braces. These are short channel bars *d* which connect adjacent helical springs. Now one of the chief features 50 of these connectors is their location. They are made in short lengths only sufficient to

bridge the space from spring to spring. For instance, the first length extends from the first spring to the second spring on one side of these two springs. The second length 60 extends from the second spring to the third spring on the opposite side of these two springs. The third length extends from the third spring to the fourth spring on the first-mentioned side of the two springs, and so 65 on, so the arrangement is a staggered one. Now this staggered arrangement of these short lengths of ties or braces is important. In the first place the employment of the 70 short lengths breaks up the braces and ties and allows a certain independent action of the helical springs which would not otherwise be possible if a continuous or solid brace was used from front to back of the seat spring. In the second place, it will be 75 noted that any helical spring which has two of these ties attached to it has the attachments on opposite sides so that the points of attachment are substantially one-half a coil apart, thereby allowing a certain amount of 80 yield between the two attachments. In the third place, by having these braces run along opposite sides of a single helical spring and attached at the sides of the 85 springs, the braces tend to maintain the helical springs in erect position at the sides as well as at front and rear.

Along the front and rear of the seat spring, a slightly different arrangement of the ties and braces is employed. Instead of 90 staggering the braces and ties in the manner above alluded to, it is more convenient to have the two ends of the two braces overlap in the manner shown in Fig. 3, that is, the end of one brace engages with the upper 95 mid coil of the helical spring and the end of the succeeding brace engages with the lower mid coil of the helical springs so that these braces are set in parallel oblique position, and the points of attachment are 100 spaced by substantially one complete coil.

These channel bar ties are very easy to attach to the springs and hence the seat springs are cheap to manufacture on account of the labor saved. All that is required in 105 attaching the ties is to use a pair of pliers to pinch the channel bar to the coils of the helical springs and no intricate tying or wire bending is necessary.

What I claim is:

1. In a seat spring, the combination of a plurality of supporting springs, a frame for

- supporting the said springs at the bottom, and ties or braces connecting the mid portions of the supporting springs and comprising short lengths arranged to reach from 5 spring to spring only, the said lengths being arranged in staggered relation across the said seat spring so that one length is on one side of two springs it connects and the next succeeding length is on the opposite side of 10 the two springs it connects.
2. In a seat spring, the combination of a supporting frame, supporting springs carried thereby, and ties or braces for connecting the mid portions of the supporting 15 springs and comprising short lengths of channel strips each bridging from one spring

to another only, the said short lengths of channel strips being arranged in staggered relation across the seat spring when viewed in plan, that is to say, one length engaging 20 the two springs it connects on one side of these two springs and the second length engaging the two springs it connects on the opposite side of such two springs, and arranged in zig-zag relation when viewed side- 25 wise, that is, the alternate lengths being disposed obliquely upward and obliquely downward.

In testimony whereof I sign this specification.

LEONARD A. YOUNG.
